LONG TRAVEL SOOT BLOWER WITH
CONTOURED RAIL

Robert E. Chappell, Lancaster, Ohio, assignor to Diamond
Power Specialty Corporation, Lancaster, Ohio, a cor-
poration of Ohio
Filed Oct. 22, 1962, Ser. No. 232,010
4 Claims. (Cl. 15—317)

The present invention broadly pertains to apparatus for cleaning the heat exchanger surfaces of heat exchanger apparatus such as high capacity power boilers and the like, and more particularly to a cleaning apparatus employing a cleaning tube provided with at least one nozzle in the forward end thereof which is movable to and from a retracted position and a projected position within the interior of a heat exchanger apparatus during which a pressurized blowing medium is discharged against the heat exchanger surfaces to be cleaned. More specifically, the present invention relates to an improved cleaning apparatus incorporating compensating means therein for compensating for the gravitational deflection of the cleaning tube during the projecting and retracting travel thereof maintaining a substantially linear path of travel of the forward nozzle end thereof assuring uniform cleaning of the heat exchanger surfaces traversed thereby.

Cleaning apparatuses of the general type to which the present invention is applicable are in widespread use in industry for effecting a removal of soot, slag, and other extraneous deposits from the surfaces of heat exchanger apparatuses of various types. Cleaning apparatuses, or soot blowers as they are conventionally referred to, of the so-called long-retracting or long-travel type, incorporate a cleaning or lance tube which is adapted to be disposed exteriorly of and in alignment with a wall port in the wall of a heat exchanger apparatus and is movable from a retracted position wherein the forward or nozzle end thereof is disposed contiguous with the wall port to a projected position within the interior of the heat exchanger apparatus. Conventionally, the lance tube is rotated during its longitudinal movement and a pressurized blowing medium such as steam or air, for example, is discharged in a helical blowing pattern from one or a plurality of nozzles disposed along the forward end portion of the lance tube. The impingement of the pressurized blowing medium against the heat exchanger surfaces effects a removal of the soot, slag and other extraneous deposits therefrom maintaining a high thermal efficiency of the heat exchanger apparatus.

The increase in the size and the capacity of modern high pressure power boilers has necessitated an increase in the length of long travel type soot blowers in order to order to achieve adequate cleaning coverage of the tube banks including the pendant type super heater and reheater bundles disposed within the interior of the boiler. The relative disposition of such tube bundles necessitates that the path of travel of the nozzles from which the blowing medium is discharged be carefully controlled so as to provide substantially uniform cleaning coverage of the heat exchanger surfaces and to avoid any mechanical interference between the lance tube and heat exchanger surfaces and attendant supporting structure.

The increasing length of the lance tube employed in long retracting type soot blowers has caused an increasing problem as a result of the gravitational deflection of the lance tube which results in an arcuate path of travel of the nozzle end portion of the lance tube creating interference and nonuniform cleaning in some instances. This vertical deflection of the nozzle end of the lance tube becomes progressively greater as the lance tube approaches the fully projected position. The resultant progressive

2

vertical deflection of the nozzle end portion of the lance tube with respect to a true linear path of travel causes a deviation in the distance of the nozzles from the heat exchanger surfaces to be cleaned resulting in a nonuniform cleaning pattern. A further problem is created when relatively closely stacked tube bundles are being cleaned whereby the close approach of the cleaning nozzles toward the heat exchanger surfaces presents the hazard of erosion of the tube bundles exposed to a close direct discharge of the blowing medium. In an attempt to overcome this lance tube deflection problem, various structural design modifications of the lance tube have been employed or proposed for use. These changes however, have been unsuccessful in eliminating lance tube deflection and have resulted in an increase in the weight, complexity and cost in long travel type soot blowers.

It is accordingly, a primary object of the present invention to provide an improved soot blower of the long retracting type which overcomes the problems associated with lance tube deflection that have been encountered in soot blowers of similar type heretofore known.

Another object of the present invention is to provide an improved long retracting type soot blower employing guide means therein which effects a controlled vertical displacement of the lance tube in an amount so as to compensate for the vertical displacement of the nozzle end portion of the lance tube as occasioned by lance tube deflection providing for a substantially linear path of travel of the nozzles relative to the heat exchanger surfaces being cleaned.

Still another object of the present invention is to provide an improved soot blower of the long retracting type which is of simple design, durable operation, of economical manufacture and which embodies compensating means therein which are readily adaptable for compensating for the vertical deflection of the nozzle end of the lance tube consistent with such factors as the length of the lance tube, the specific direction of travel thereof, and the clearance and interference characteristics of the heat exchanger surfaces to be cleaned.

Other objects and advantages of the present invention will become apparent from the following detailed description taken in conjunction with the accompanying drawings, wherein:

45 FIGURE 1 is a longitudinal side elevation view of a soot blower constructed in accordance with the preferred embodiments of the present invention and illustrated in two sections which are connected to each other along the lines indicated at A—A;

50 FIG. 2 is a fragmentary perspective view of the forward end portion of the soot blower shown in FIGURE 1;

FIG. 3 is a fragmentary end elevation view partly in section of the forward end of a lance tube employed in the soot blower shown in FIGURE 1;

55 FIG. 4 is an alternate satisfactory form of a nozzle arrangement in the forward end portion of a lance tube;

FIG. 5 is a graphical illustration of the vertical deflection of a typical lance tube as a function of its longitudinal projecting position, and

60 FIG. 6 is a typical substantially linear path of travel of the nozzle end of a lance tube of a long retracting type soot blower incorporating compensating means in accordance with the present invention.

Referring now in detail to the drawings and as may be best seen in FIGURES 1-2, a long retracting or long travel type soot blower to which the present invention is applicable, comprises guide means such as a rail 10 which is adapted to be positioned exteriorly of a wall 12 of a heat exchanger apparatus provided with an opening or wall port 14 therethrough. A carriage 16 is movably supported on a track plate 18 affixed to the underside of the lower flange of the rail 10 such as by rollers 20 dis-

posed in rolling bearing contact against the upper projecting surface of the track plate. The carrier 16 is movable along the rail 10 from a fully retracted position as shown in FIGURE 1 to a fully projected position in which the carriage is positioned at the forward end portion of the rail 10 adjacent to the wall 12 of the heat exchanger apparatus.

A lance tube 22 is rotatably supported at the rearward end thereof by the carriage 16 and extends therefrom in a direction in alignment with the wall port 14. The forward end portion of the lance tube 22 is rotatably and movably supported by suitable supporting means such as a roller support 24 connected to the forward end of the rail 10 and is disposed adjacent to the wall port 14. When lance tubes such as the lance tube 22 of a substantially long length are employed, a sag or deflection of the lance tube will occur between the forward roller support 24 and the carriage 16. In such cases, it is usually desirable to employ an intermediate support such as the intermediate roller support 26 as shown in FIGURE 1, which supports the mid-portion of the lance tube while in the fully retracted position as well as during its projecting and retracting travel.

The forward roller support 24 as best seen in FIGURE 2, comprises a yoke-shaped member 28 affixed to and depending from the forward end of the rail 10. A roller bracket 30 is pivotally secured by means of a pin 32 to the lower portion of each of the legs of the yoke-shaped member 28. A roller 34 is rotatably mounted in each of the roller brackets 30 and is adapted to rotatably and slidably contact the peripheral surface of the lance tube 22. A bracket 36 is connected to the lower end of the yoke-shaped member 28 and is provided with a pair of adjusting screws 38 which extend upwardly and are disposed with the ends of the shank portions thereof in abutting relationship against the undersides of the roller brackets 30 providing for appropriate vertical adjustment of the lance tube relative to the wall port 14.

The intermediate roller support 26 which is usually employed when lance tubes of about 25 feet or greater in length are used, comprises a trolley bracket 40 which is disposed in rolling engagement on the track plate 18 of the rail 10, and is movable therealong from a position substantially in the middle of the rail when the carriage is in the fully retracted position to a position adjacent to the wall port 14 along the forward end portion of the rail when the carriage and the lance tube are in the fully projected position. The intermediate roller support 26 is movable from the mid-position to the forward position in response to the projecting travel of the carriage and is retracted to the mid-position by suitable latching means on the carriage which are disengaged when the intermediate roller support attains the mid-position during the retracted travel of the carriage. The lower portion of the intermediate roller support 26 is provided with suitable sliding or rolling supports on which the peripheral surface of the lance tube is rotatably and movably disposed.

The forward end of the lance tube 22 is slidably disposed within the wall port 14 which conventionally incorporates suitable sealing means (not shown) for preventing the escape of the hot combustion gases from within the interior of the heat exchanger apparatus through the wall port. The forward end of the lance tube as best seen in FIGURES 3 and 4, is provided with one or more nozzles through which a pressurized blowing medium such as air or steam, for example, is discharged during the traversing movement of the lance tube during a cleaning operation. In the particular arrangement shown in FIGURE 3, a pair of diametrically disposed nozzles 42 are provided in the nozzle end of the lance tube 22 which discharge the blowing medium in a direction substantially perpendicular to the longitudinal axis of the lance tube.

An alternate satisfactory arrangement is illustrated in FIGURE 4 wherein a nozzle 44 is provided for discharging

the blowing medium in a direction substantially perpendicular to the axis of the lance tube 22 and an angularly disposed nozzle 46 is incorporated for discharging the blowing medium in a direction forwardly of and angularly inclined relative to the longitudinal axis of the lance tube. The use of one or more angularly inclined nozzles in accordance with the embodiment shown in FIGURE 4 provides advantages in some installations particularly when the angle of deflection of the nozzle end of the lance tube becomes relatively large. In either event, the particular type of nozzle arrangement employed is selected in consideration of the nature and configuration of the heat exchanger surfaces to be cleaned so as to provide substantially uniform coverage and optimum cleaning action.

When the lance tube 22 is in the fully retracted position, the nozzle end thereof is disposed in the wall port 14 whereby the nozzle end of the lance tube is protected from the hot combustion gases within the interior of the heat exchanger apparatus. At the initiation of the operation of the soot blower, the lance tube commences to rotate and is advanced from the fully retracted position outwardly toward the projected position. The discharge of the blowing medium from the nozzle in the forward end of the lance tube is delayed until the lance tube has travelled to a position slightly beyond the water wall tubes 48 positioned along the inner surface of the heat exchanger apparatus. Similarly, the discharge of the blowing medium from the nozzle is halted prior to the completion of the retracting movement of the lance tube when the nozzles approach a position spaced from the water wall tubes 48 to avoid direct close range impingement of the blowing medium thereagainst which may result in the erosion thereof.

The supply of a pressurized blowing medium to the interior of the lance tube 22 is conveniently achieved by a feed tube 50 that is stationarily connected at its rearward end to a supply valve 52 mounted at the outward end of the rail 10. The supply valve 52 is connected to a suitable supply conduit 54 which is disposed in communication with a main supply header (not shown) to which each of the other soot blowers mounted on the heat exchanger apparatus may suitably be connected.

The supply valve 52 can be operated mechanically such as by linkage 55 responsible to the coaction with the carriage 16 during its longitudinal movement along the rail 10 and is conventionally moved to an open position when the carriage has advanced to a position wherein the nozzle end of the lance tube is disposed beyond the water wall tubes 48 along the inner surface of the heat exchanger apparatus. Alternatively, the supply valve 52 can be actuated by a suitable solenoid operative responsive to the tripping of suitable limit switches by the carriage in response to its movement between the fully projected position and retracted position.

The feed tube 50 extends forwardly from the supply valve 52 and is disposed in telescopic relationship within the interior of the lance tube 22. The feed tube extends for substantially the entire length of the rail 10 to assure constant communication with the interior of the lance tube as the carriage is advanced to the fully projected position. Suitable sealing means (not shown) are incorporated in the carriage 16 providing a pressure-tight connection between the periphery of the feed tube and the inner surface of the lance tube to prevent the escape of any pressurized blowing medium therebetween.

Since the feed tube is substantially the same length as the lance tube, there is a tendency for the feed tube to sag when the carriage and lance tube are in the fully projected position. When the length of the feed tube is relatively great, it is usually preferred to provide a feed tube support roller 56 as shown in FIGURE 1 which is movably mounted on the rail 10 in a manner similar to the intermediate roller support 26 and is movable by the carriage 16 to a position substantially at the mid-

point of the rail 10. Suitable stop means are provided on the feed tube support roller 56 and the rail 10 to prevent further movement of the feed tube support roller beyond the midpoint of the rail during the continued advancing movement of the carriage. The feed tube support roller 56 is returned to the fully retracted position as shown in FIGURE 1 by the coaction with the carriage during the latter half of its retracting movement. By virtue of this arrangement, the sag of the feed tube is minimized when the carriage is on the fully projected position by providing support at substantially the mid-point thereof preventing any binding or skewing of the feed tube during its telescopic sliding movement into and out of the lance tube.

The movement of the carriage 16 and lance tube as well as the simultaneous rotation of the lance tube during its projecting and retracting travel is achieved in accordance with the exemplary construction shown in the drawings by a reversible motor 58 drivingly connected to a gear box 60 mounted adjacent to the forward end of the rail 10 as may be best seen in FIGURE 2. The reversible motor 58 may either be of a fluid actuatable type such as an air or hydraulic motor or, alternatively, may comprise a reversible electric motor. The output shaft of the gear box 60 is drivingly coupled to a suitable elongated drive shaft 62 of an irregular cross section such as a square cross section, for example, which extends substantially for the entire length of the rail 10 and is slidably and rotatably coupled to a driven member on the carriage having a correspondingly contoured bore therethrough for slidably engaging the drive shaft. The driven member on the carriage may suitably be coupled to suitable gears for effecting rotation of the lance tube and for translation of the carriage along the rail 10.

In the exemplary embodiment shown in the drawings, the translation of the carriage between the projected and retracted positions is achieved by a rack 64 affixed to and extending centrally of the under side of the rail 10 with which a pinion 66 is disposed in constant meshing relationship and which is drivingly connected to the drive shaft 62 by the driven member on the carriage. In accordance with this arrangement, the rotation of the reversible motor 58 in one direction effects movement of the carriage and translation and rotation of the lance tube in one direction and upon reversal of the direction of rotation of the reversible motor, the direction of rotation and translation of the lance tube is likewise reversed.

Energization of the reversible motor can be achieved manually or remotely by the operator or alternatively, can be achieved in accordance with a preselected sequentially phased operating cycle as controlled by an automatic control system. On energization of the reversible motor, the carriage commences to advance toward the projected position until it trips a suitable sensing device such as a limit switch LS1 mounted on the rail 10 as shown in FIGURE 1. The tripping of the forward control limit switch LS1 signals the control circuit of the soot blower which reverses the direction of rotation of the reversible motor whereby the carriage commences its retracting movement. When the fully retracted position is attained, the carriage actuates a suitable sensing device such as a rear travel limit switch LS2 which signals the control circuit and de-energizes the reversible motor. The carriage and lance tube remain in the fully retracted position preparatory to the next cleaning cycle.

Alternate satisfactory power means for effecting movement of the carriage and lance tube along the rail can be achieved by installing a suitable electric or fluid actuated reversible motor directly on the carriage 16 which is drivingly connected to the pinion 66 and the gearing for rotating the lance tube. Alternatively, the reversible motor 58 and gear box 60 as shown in FIGURES 1 and 2, can be mounted at the rearward end of the rail 10 adjacent to the supply valve providing the

same driving action as hereinbefore described. The motor means as well as the entire rail of the soot blower is preferably protected by a suitable canopy or shroud 68 to protect the several components of the soot blower from the elements and any dust or dirt particles which might interfere with the proper function thereof.

It will be apparent from the description of the soot blower as hereinabove set forth that, as the lance tube 22 is moved from the fully retracted position as shown in FIGURE 1 toward the projected position, the nozzle end portion of the lance tube will progressively bend downwardly in a vertical direction in response to the gravitational bending or deflection of the overhanging portion of the lance tube between the nozzle end and the front roller support 24 disposed adjacent to the wall port 14. A typical graphical illustration of the vertical deflection of the nozzle end portion of a lance tube is illustrated in FIGURE 5 as a function of the projecting position of the lance tube from the front roller support. As shown in FIGURE 5, the vertical deflection expressed in inches of the nozzle end portion of a non-compensated lance tube having a length of 45 feet attains a magnitude of almost 3 feet at the point of maximum projection. This necessitates a relatively large cavity in the tube bundles to provide satisfactory clearance for the lance tube in addition to causing a non-uniform cleaning pattern.

The specific deflection obtained on a lance tube will vary, depending on the specific physical characteristics of the material of which it is comprised as well as the weight, diameter, and wall construction thereof. This deflection occurs whether the lance tube travels in a substantially horizontal plane or is angularly inclined from the horizontal in accordance with a specific layout of the tube bundles and heat exchanger surfaces. In either event, it will be apparent that a deviation in the position of the nozzles in the nozzle end of the lance tube occurs between the initial portion of its outward travel and at the fully projected position which, if not compensated for, results in an unevenness in the cleaning action as well as in some instances producing mechanical interference and erosion of the tubes being cleaned.

In accordance with the practice of the present invention, the vertical deflection of the lance tube is compensated for so as to provide a substantially linear path of travel of the nozzle end portion thereof between the fully retracted and the fully projected positions. In the specific embodiment shown, the compensation is achieved by providing an appropriate contour in at least a portion of the rail 10 whereby the carriage and the rearward end of the lance tube 22 is vertically displaced in response to the longitudinal travel of the carriage therealong providing a corresponding corrective vertical displacement of the nozzle end portion of the lance tube. A graphical illustration of a compensated path of travel of the nozzle end portion of the lance is illustrated in FIGURE 6 wherein it is noted that the deviation of the path of travel of the nozzle end from a true linear path is relatively low throughout the entire travel of the lance tube.

The particular path of travel of the nozzle end of the lance tube as shown in FIGURE 6 was obtained on the same soot blower employed for tabulating the curve shown in FIGURE 5. The soot blower was not provided with an intermediate roller support such as the support 26 as shown in FIGURE 1 whereby a sagging of the lance tube in the fully retracted position occurred. As a result of this sag, the initial outward movement of the lance tube produced an upward movement of the nozzle end above the horizontal zero reference line. As the nozzle subsequently approached the zero line, the compensating means hereinafter described effect correction of the downward nozzle deflection maintaining a substantially linear path in comparison to the arcuate path of the non-compensated lance tube shown in FIGURE 5.

The corrective deflection of the nozzle end portion of the lance tube is achieved, as may be best seen in FIG-

URE 1, by providing an arcuately vertically depressed contour along at least a portion of the rail 10 which deviates from a reference line indicated generally at 70 by a magnitude selected relative to the longitudinal spacing thereof from the front roller support 24 to provide an angular deviation of the outer end portion of the lance tube relative to the reference line that will effect a vertical lifting of the nozzle end portion of the lance tube in an amount sufficient to place it in a position substantially coinciding with a linear path of travel.

In accordance with this relationship, the rearward end portion of the rail 10 along the section generally designated as W is of a substantially straight configuration corresponding substantially to the plane of the reference line 70. The length of the section W is dictated by the length of the overhanging portion of the lance tube beyond the wall port 14 which will produce only a negligible deflection from the linear path of travel obviating the need of any compensation. The rail 10 then commences a downward arcuate contour as provided by the section generally indicated at X until a point generally indicated at Y of maximum deviation of the rail from the reference line 70 is attained. During the movement of the carriage along the rail section X to the point Y, the rearward end of the lance tube is vertically moved downwardly effecting a corresponding upward vertical movement of the lance tube about the fulcrum provided by the forward roller support 24 compensating for the progressive increase in the deflection of the nozzle end portion of the lance tube relative to the front support.

Movement of the carriage toward the fully projected position beyond the point Y is achieved along a track section generally indicated at Z which is arcuately inclined upwardly and progressively approaches the reference line 70. The decrease in the vertical deflection of the rail section Z relative to the reference line 70 is necessitated by the decrease in the length of the leverage arm between the front roller support 24 and the carriage 16 which provides for a magnification of the vertical correction of the nozzle end portion of the lance tube as the carriage approaches the fully projected position. Accordingly, the angularity of the portion of the lance tube disposed exteriorly of the wall of the heat exchanger apparatus decreases as the carriage moves along the rail section Z toward the projected position whereby the nozzle end portion of the lance tube is maintained in a substantially linear path of travel. A corresponding correction of the deflection of the nozzle end portion of the lance tube is achieved during the retracting movement of the lance tube providing therewith a substantially linear path of the retracting travel of the nozzle end thereof. The corrective action supplied by the arcuate contour of the rail sections W, X and Z, is illustrated in FIGURE 6 and corresponds to that achieved by the contoured rail having a configuration as shown in FIGURE 1.

A rail contoured in accordance with the configuration as shown in FIGURE 1 is effective to provide a substantially linear path of travel of the nozzle end portion of the lance tube in accordance with the graph as portrayed in FIGURE 6. As shown in this figure, the maximum deviation of the nozzle end portion of the lance tube from a true linear path throughout its travel is less than 7 inches in comparison to a maximum deflection of almost 3 feet of a non-compensated lance tube as portrayed in FIGURE 5. A further improvement in the linearity of the path of travel of the nozzle end of the lance tube can be provided by incorporating an intermediate roller support such as the roller support 26 shown in FIGURE 1 whereby the sag of the lance tube when the carriage is in the fully retracted position is substantially eliminated. The elimination of this sag is effective to eliminate the upward deviation of the nozzle end portion of the lance tube from the true linear path as shown in FIGURE 6 during the first 25 feet of travel providing for a substantially linear path throughout the entire projecting and

retracting travel thereof. Tests conducted on the soot blower employing such an intermediate roller support reduced deviations of the nozzle end of the lance tube to less than 3 inches above and below the theoretical reference line.

Further improvements and compensation of the deflection of the nozzle end portion of the lance tube can be achieved by varying the height of the front roller support 24 and the wall port 14 relative to the linear reference line effecting a change in the fulcrum about which the lance tube bends providing additional correction in combination with that provided by the contoured rail. It will be further noted that the contoured portion of the rail is comprised of a series of straight sections rigidly affixed in end-abutting relationship to provide the desired contour. By employing a rail 10 which is formed in a smooth arcuate curvature along the contoured section thereof, more accurate control of the path of travel of the lance tube can be achieved. It will also be understood that by further modifying the particular contour of the rail 10 consistent with a particular type of lance tube, a path of travel of the nozzle end portion thereof can be achieved which is in a true linear direction coinciding with the horizontal zero reference line as shown in FIGURE 6. For practical purposes, however, lance tube deflections of a magnitude as illustrated in FIGURE 6 are suitable for most installations and are sufficient to achieve satisfactory uniform cleaning of the heat exchanger surfaces traversed thereby.

While it will be apparent that the preferred embodiments of the invention disclosed are well calculated to fulfill the objects above stated, it will be appreciated that the invention is susceptible to modification, variation and change without departing from the proper scope or fair meaning of the subjoined claims.

What is claimed is:

1. A long travel soot blower comprising an elongated rail, a carriage movably mounted on said rail, a lance tube having the rearward end thereof movably supported on said carriage and extending therefrom in a direction in alignment with a wall port in the wall of a heat exchanger apparatus, said lance tube formed at its forward end with at least one nozzle for discharging a pressurized blowing medium against the heat exchanger surfaces to be cleaned, means for rotating said lance tube and for moving said carriage and said lance tube to and from a retracted position and a projected position, support means disposed adjacent to the wall port for movably supporting said lance tube while in said projected and retracted positions and during its movement therebetween, at least a portion of said rail formed with a contour vertically displaced from a reference plane extending between the ends of said rail for vertically moving said carriage and said rearward end of said lance tube relative to said support means in response to movement of said carriage along said rail compensating for the gravitational deflection of said lance tube and providing for a substantially linear path of travel of the nozzle end of said lance tube between said positions.

2. A long travel soot blower comprising an elongated rail adapted to be disposed exteriorly of a heat exchanger apparatus, a carriage movably mounted on said rail, a lance tube having the rearward end thereof movably supported on said carriage and extending therefrom in a direction in alignment with a wall port in a wall of a heat exchanger apparatus, said lance tube formed at its forward end with at least one nozzle for discharging a pressurized blowing medium against the heat exchanger surfaces to be cleaned, power means for rotating said lance tube and for moving said carriage and said lance tube to and from a retracted position wherein the nozzle end of said lance tube is disposed contiguous to the wall port and a projected position wherein said nozzle end is disposed within the interior of the heat exchanger apparatus, support means disposed adjacent to the wall

port for movably supporting said lance tube, at least a portion of said rail formed with a contour vertically displaced from a reference plane extending between the ends of said rail for vertically moving said carriage and said rearward end of said lance tube relative to said support means in response to the longitudinal travel of said carriage along said rail and compensating for the gravitational deflection of said lance tube providing for a substantially linear path of travel of said nozzle end between said projected and said retracted positions.

3. A long travel soot blower comprising an elongated rail adapted to be disposed in a substantially horizontal stationary position exteriorly of a heat exchanger apparatus, a carriage movably mounted on said rail, a lance tube having the rearward end thereof movably supported on said carriage and extending therefrom in a direction in alignment with a wall port in a wall of a heat exchanger apparatus, said lance tube formed at its forward end with at least one nozzle for discharging a pressurized blowing medium against the heat exchanger surfaces to be cleaned, power means for rotating said lance tube and for moving said carriage and said lance tube in a substantially horizontal direction along said rail to and from a retracted position and a projected position, support means for movably supporting said lance tube at a position adjacent to the wall port, at least a portion of said rail formed with a longitudinally extending contour vertically displaced from a horizontal reference plane extending between the ends of said rail for vertically moving said rearward end of said lance tube relative to said support means in response to the longitudinal travel of said carriage along said rail and compensating for the gravitational deflection of said lance tube during the projecting and retracting travel thereof and providing for a substantially linear path of travel of the nozzle end thereof between said projected and said retracted positions.

4. A long travel soot blower comprising a rail adapted to be disposed exteriorly of a heat exchanger apparatus, a carriage movably mounted on said rail, a lance tube having the rearward end thereof movable and rotatably supported on said carriage and extending therefrom in a direction in alignment with a wall port in a wall of a heat exchanger apparatus, said lance tube formed at its forward end with at least one nozzle for discharging a pressurized blowing medium against the heat exchanger surfaces to be cleaned, power means for rotating said lance tube and for moving said carriage and said lance tube to and from a retracted position and a projected position, supporting means for movably supporting said lance tube at a position adjacent to the wall box, at least a portion of said rail formed with a vertically disposed arcuate contour for vertically moving said rearward end of said lance tube relative to said supporting means responsive to the longitudinal travel of said carriage compensating for the gravitational deflection of said lance tube and providing for a substantially linear path of travel of the nozzle end of said lance tube between said retracted and said projected positions.
